(57) **CLAIM**

We claim the ornamental design for a knife, as shown and described.

DESCRIPTION

FIG. 1 is a front top perspective view of a knife showing our new design;

FIG. 2 is a front view of the knife of FIG. 1;

FIG. 3 is a rear view of the knife of FIG. 1;

FIG. 4 is a left side view of the knife of FIG. 1;

FIG. 5 is a right side view of the knife of FIG. 1;

FIG. 6 is a top view of the knife of FIG. 1;

FIG. 7 is a bottom view of the knife of FIG. 1; and,

FIG. 8 is a rear top perspective view of the knife of FIG. 1. The broken lines in the drawings illustrate features of the knife that form no part of the claim.
